(57) **CLAIM**

We claim the ornamental design for camera mount, as shown and described.

DESCRIPTION

FIG. 1 is a top, front and left side perspective view of a camera mount, showing our new design;

FIG. 2 is a front elevation view of the design shown in FIG. 1;

FIG. 3 is a rear elevation view of the design shown in FIG. 1;

FIG. 4 is a left side elevation view of the design shown in FIG. 1;

FIG. 5 is a right side elevation view of the design shown in FIG. 1;

FIG. 6 is a top plan view of the design shown in FIG. 1;

FIG. 7 is a bottom plan view of the design shown in FIG. 1;

FIG. 8 is a top, front and right side perspective view of the design shown in FIG. 1, shown in condition of use with a camera disclosed in broken lines to illustrate an environment;

FIG. 9 is a front elevation view of the design shown in FIG. 8;

FIG. 10 is a rear elevation view of the design shown in FIG. 8;

FIG. 11 is a left side elevation view of the design shown in FIG. 8;

FIG. 12 is a right side elevation view of the design shown in FIG. 8;

FIG. 13 is a top plan view of the design shown in FIG. 8; and,

FIG. 14 is a bottom plan view of the design shown in FIG. 8.

(Continued)

The broken lines in the drawings depict portions of the camera mount, and forms no part of the claimed design. The additional broken lines seen in FIG. 8, FIG. 9, and FIGS. 11-14 depict environment, and forms no part of the claimed design.

1 Claim, 14 Drawing Sheets
